JOHN FARRELL, OF NEWTON, NEW JERSEY.

POWER HOIST MECHANISM.

Application filed February 12, 1924. Serial No. 692,290.

This invention relates, generally, to improvements in power hoists; and the invention has reference, more particularly to hoisting mechanism having a plurality of drums operated by friction clutch transmission mechanism, and provided with a novel single lever control mechanism by means of which the operation of the drums may be selectively controlled at will.

10 The invention has for its principal object to provide a very simple and yet efficient single lever control mechanism for hoisting machines possessing a plurality of drums, whereby the drums may be selectively put into operation, said single lever control mechanism being of such novel construction that it may, if desired, be actuated from a distance by means of a single rope attached to the hand lever.

15 The invention also has for another object to provide various detail improvements in power hoists of the kind described, such as an improved construction of brake mechanism for the main drum, and an improved 20 means for adjusting the friction blocks of the drum clutch mechanism.

Other objects of the invention, not at this time more particularly enumerated, will be clearly understood from the following detailed description of the same.

With the various objects of this invention in view, the same consists, primarily, in the novel construction of power hoist mechanism hereinafter set forth; and, the invention consists, furthermore, in the novel arrangements and combinations of the various devices and parts, as well as in the details of the construction of the same, all of which will be hereinafter more fully described, and 40 then finally embodied in the claims appended to this specification.

The invention is clearly illustrated in the accompanying drawings, in which:—

Figure 1 is a plan view of the novel construction of power hoist mechanism made according to and embodying the principles of this invention; Figure 2 is a side elevation of the same; Figure 3 is a fragmentary longitudinal vertical section, taken on line 3—3 in said Figure 1 and drawn on an enlarged scale, said view showing the novel single lever control mechanism in neutral position by full lines, and in the selective operative positions by dotted lines; Figure 4 is a fragmentary vertical cross section, taken on line 4—4 in said Figure 3; Figure

5 is a fragmentary detail horizontal section on an enlarged scale, illustrating the novel means for adjusting the friction blocks of the drum clutch mechanism; Figure 6 is a 60 face view of one of the friction blocks as supported and carried by said adjusting means; and Figure 7 is a perspective view of the friction block adjusting means alone.

Figure 8 is a plan view of a somewhat 65 modified construction of power hoist mechanism which embodies, however, the principles of the present invention; and Figure 9 is a fragmentary vertical cross-section, taken on line 9—9 in said Figure 8.

70 Figure 10 is a view similar to that shown in Figure 3, but illustrating another modified construction of the power hoist control mechanism made according to and embodying the principles of this invention; and Figure 11 is a fragmentary vertical cross section, taken on line 11—11 in said Figure 10.

Similar characters of reference are employed in all of the hereinabove described 80 views, to indicate corresponding parts.

Referring now to said drawings, the reference character 10 indicates one side frame and 11 indicates the other side frame upon which the hoisting mechanism is mounted. 85 Each side frame is provided intermediate its ends with a bearing member 12. Journaled in said bearing members 12, so as to extend transversely between said bearing members 12 is a drive shaft 13, having affixed to one end a belt pulley 14, or other suitable means for applying power thereto. Fixed upon said drive shaft 13, adjacent to the inner side of the side frame 10, is a 90 spur gear 15.

95 Each side frame is further provided, adjacent to its one end, with a bearing member 16. Extending transversely between said bearing members 16, and suitably affixed thereto, is a non-rotatable shaft 17. Supported upon said shaft 17, adjacent to the inner side of said side frame 10, and so as to freely rotate thereon, is a gear wheel 18, which operatively meshes with and is driven by said spur gear 15 of the drive shaft 13. 100 Mounted upon the inwardly facing side of said gear wheel 18 are a plurality of friction blocks 19, the outer ends of which are shaped to provide inclined friction faces 20. Each friction block 19 is adjustably supported by a novel means, the same comprising a cylindrical main body 21 which ex-

tends through and is rotatably mounted in the body of the gear wheel 18. Said cylindrical body 21 is provided at its outer end with an enlarged head 22, which engages 5 the outer face of the gear wheel body to prevent inward longitudinal displacement of said cylindrical body 21. Projecting from the inner end of said cylindrical body 21 is an eccentrically off-set carrier stud 23, which extends through the friction block 19, and which supports the same. The cylindrical body 21 and the carrier stud 23 are together provided with a longitudinally extending through opening 24. Extending 10 through said opening 24 is a bolt 25 having at its inner end a head 26, which, with a washer 27, bears against the friction block 19. The outer end of said bolt 25 is threaded to receive a nut 28. When it is 15 desired to adjust the friction block, to compensate for wear or for any other reason, the nut 28 is loosened, and the cylindrical body 21 is turned to rotate the eccentrically off-set carrier stud 23, which by reason of 20 its eccentricity relative to the axis of the cylindrical body 21, will cause the friction block to be shifted outwardly or inwardly, as the occasion may require. When the desired adjustment of the friction block has 25 thus been made, the same may be locked or fixed in the desired adjusted position by again tightening up the nut 28, whereby the head 26 of the bolt 25 draws the friction block 19 into strong frictionally bound or 30 clamped relation to the inner surface of the gear wheel 18, all of which will be readily understood from an inspection of Figures 5, 6 and 7 of the drawings.

The reference character 29 indicates a 40 main hoisting drum which is loosely mounted upon the shaft 17, and which is also capable of a slight longitudinal shifting movement on said shaft 17. The flange of said drum 29, which is adjacent to said gear wheel 18, is provided with an annular clutch member 30, the inner side of which is inclined to provide a friction face 31 adapted 45 to conform to and receive the engagement faces 20 of the friction blocks 19, when said parts are operatively engaged together by shifting the drum 29 longitudinally toward the gear wheel 18. A compression spring 32 is disposed around the shaft 17 intermediate the hubs of said gear wheel 18 and said drum 29 to normally hold the drum clutch member 30 disengaged from the friction blocks 19 of the gear wheel 18.

Each side frame is further provided, adjacent to its opposite end, with a bearing member 33. Extending transversely between said bearing members 33, and suitably affixed thereto, is a non-rotatable shaft 34. Supported upon said shaft 34, adjacent to the inner side of said side frame 10, and so 60 as to freely rotate thereon, is a gear wheel 35, which operatively meshes with and is driven by said spur gear 15 of the drive shaft 13. Said gear wheel 35 is provided on its inwardly facing side with an annular flange which provides a female clutch member 36. The reference character 37 indicates an auxiliary or return hoisting drum which is loosely mounted upon the shaft 34, and which is also capable of a slight longitudinal shifting movement on said shaft 34. 70 The flange of said drum 37, which is adjacent to the gear wheel 35, is provided with a male clutch member 38 adapted to frictionally engage the female clutch member 36 of the said gear wheel 35, when said drum 80 37 is shifted longitudinally toward said gear wheel 35. Means such as a spring (not shown) disposed and arranged in a cooperative relation between the gear wheel 35 and drum 37, similar to the above described relation of the spring 32 to and between the main drum 29 and the gear wheel 18, may be employed to normally hold the drum clutch member 38 disengaged from the female clutch member 36 of the gear wheel 35. 85

The novel single lever control means for selectively shifting either one or the other of said drums into clutched relation to the power transmission mechanism, comprises the following elements: 90

Connected with the bearing member 16 of the side frame 11 is an inwardly projecting boss or hub 39, the free end of which is shaped to provide a stationary end-thrust cam 40. Fulcrumed on the shaft 17, intermediate the adjacent hub-portion 41 of said hoisting drum 29 and said sleeve or hub 39, is a bell-crank device, consisting of a fulcrum sleeve 42 journaled on said shaft 17; said fulcrum sleeve having an upwardly extending crank-arm 43, and a laterally projecting crank-arm 44 which projects toward the hoisting drum 37. The outer end of said fulcrum sleeve is shaped to provide a movable end-thrust cam 45, which abuts and cooperates with said stationary end-thrust cam 40. 100

Associated with said bell-crank device is a yieldable stop means, which cooperates with a fixed stop nosing 46 with which the upper surface of said boss or hub 39 is provided, and which is adapted to normally engage the latter to determine the normal initial or neutral position of said bell-crank device and of the cam means with which the latter is provided. Said yieldable stop means comprises a housing member 47 provided with laterally and oppositely projecting wings or lugs 48 through which extend bolts 49, or other suitable fastening means, whereby said housing member 47 may be secured to the outer side of said bell-crank device. Said housing member 47 is so disposed, when operatively connected with said bell-crank device, as to project longitudinally forward 110

115

120

125

130

so as to overhang said stationary boss or hub 39. Said housing member 47 is provided at its lower or under side with a socket 50 in which is arranged a stop-roller 51. Extending upwardly through said housing member 47 above said socket 50 is a vertical bore 52 in which is arranged a compression spring 53, which thrusts downwardly upon said stop-roller 51 to yieldably engage the latter with the upper surface of said boss or hub 39. The tension of said spring 53 is regulated by an adjusting screw 54 which is threaded into the bore 52 from the upper end of said housing member 47.

Suitably secured to the upwardly extending crank-arm 43 of the bell-crank device is a control lever 55. If the mechanism is to be controlled by an operator stationed at the hoist, said control lever may be so affixed to said bell-crank device as to project vertically upward therefrom; if, however, the mechanism is to be controlled from a distance through the intermediation of a pull rope, as 56, attached to the control lever, then it is preferable that the latter be so affixed to the crank-arm 43 as to incline from the vertical, or, in other words, to extend obliquely upward in a direction toward the auxiliary hoisting drum. In the latter arrangement or disposition of said control lever, the same is provided, adjacent to its free end with a weight member 57, so that when the pull rope 56 is relaxed, the force of gravity acting on the weight will swing the lever in a direction opposite to that in which it is moved by a pull upon said rope.

Normally the bell-crank device and its end thrust cam means is disposed in a neutral position wherein the stop-roller 51 is held stopped against the stop-nosing 46, and as an aid to holding and returning the parts to such neutral position, the fulcrum sleeve 42 of said bell-crank device is provided on its underside with a perforate ear or lug 58 to which is attached one end of a pull spring 59, the opposite end of which is anchored to the side frame 11, by connection thereof with an anchor post 60 with which said side frame is provided.

That part of the single lever control mechanism which cooperates with the auxiliary drum 37, comprises a wedge-plate 61, which is preferably bifurcated so as to straddle the shaft 34 on which said drum 37 is mounted. Said wedge-plate 61 is adapted to bear against the hub-portion 62 of said auxiliary drum 37, and, if desired, one or more washers 63 may be interposed between said hub-portion 62 and said wedge-plate 61. Fixed on said shaft 34 is a collar or thrust-block 64 provided on its inner face with thrust-lugs 65 against which the wedge-plate is backed. Said wedge-plate 61 is interconnected with said bell-crank device by a link bar 66 which is pivotally connected by one

end to said wedge-block, and by its other end to said laterally projecting crank-arm 44 of said bell-crank device, preferably by means of one of the fastening bolts 49.

The hoisting mechanism, constructed as above described, is further provided, in connection with the main drum 29, with a novel construction and arrangement of brake mechanism. This brake mechanism comprises an annular brake drum flange 67, which projects from one end of the drum 29. Connected with and projecting inwardly from the side frame 11 is a fulcrum stud 68 upon which is pivotally mounted a bell-crank lever 68, to one arm 69 of which is suitably connected one end of a brake-band 70, which encircles said brake drum flange 67, and the other arm 71 of which is provided, intermediate its ends with an anchor arm 72, to which the opposite end of said brake-band 70 is connected. A helical spring 73 encircles the hub portion of said bell-crank lever 68, and one branch thereof is anchored on an anchor pin 74 which projects inwardly from said side frame 11, and the other branch of which is connected with an attachment stud 75 with which the arm 69 of the bell-crank lever is provided. The tension of said spring 73 tends to normally return said bell-crank lever to a normal initial brake-band releasing position. Said bell-crank lever is operated, to in turn actuate said brake-band 70, by means of an operating lever 76, which is fulcrumed on said side frame 11, and pivotally interconnected, at a point intermediate its free end and its fulcrum, with the end of said arm 71 of said bell-crank lever by means of a coupling pin 77. The free end of said operating lever 78 terminates in a flat treadle portion 78.

The side frame 11 is provided with a plurality of ratchet teeth 79 with which said operating lever 76 may be selectively engaged, when the same is depressed to operate said bell-crank lever and thus in turn actuate said brake-band 70, thus holding the brake-band in braking relation to the brake drum flange 67, when it is desired so to do. It will be understood, from an inspection of Figures 1 and 2 more particularly, that the depression or downward swinging movement of the operating lever 76 will swing downwardly the bell-crank lever arm 71 and outwardly the bell-crank lever arm 69, whereby the brake-band 70 is contracted about the brake drum flange 67. It will also be understood that the interrelation of the bell-crank lever 68 and operating lever 76 is such that the leverage is compounded, so that comparatively little force applied to the latter will be increased or compounded to produce a very powerful contraction of the brake-band 70 relative to the brake drum flange 67.

The novel construction of hoisting mech-

anism above described is particularly adapted for hay handling, for hoisting ice into ice houses, for coal handling and many other hoisting operations. In many of such hoisting operations it is desirable for the operator to be enabled to control the operation of the hoisting drums from a distance, as, for example, when handling hay, to be able to control the operation of the hoisting drums from the top of a load of hay, whereby the operator may both attend the handling of the hay-fork in loading the same, as well as the control of the hoisting drums. To this end the novel single lever control mechanism above described is readily and efficiently adapted. In hay handling the main drum 29 is utilized to lift the load and to operate an overhead carriage for running the loaded hay-fork into the barn and hay-mow. Assume that the hay-fork has been lowered to the top of a loaded wagon and charged or loaded with hay to be hoisted up and run into the barn and mow. When ready to hoist, the operator pulls upon the rope or line 56 which swings the control lever 55 to the left, thus rotating the bell-crank device so that the end thrust cam 45 of its fulcrum sleeve 42 is operatively rotated against the stationary end thrust cam 40. Such actuation of the cam devices causes the sleeve 42 to shift inwardly upon the shaft 17, and in turn shifts the main drum 29 to cause the clutch mechanism intermediate the same and the rotating gear wheel 18 to engage, so that power is transmitted to the drum 29 and the loaded hay-fork is thereupon lifted up to the entrance of the barn and mow (the described operation of the hoist control mechanism being illustrated by the dotted representation of the same shown in Figure 3 and indicated by the reference character *x*). The loaded hay-fork having thus been hoisted to the overhead conveyer or carriage and then to the desired position in the mow, the operator relaxes the rope or line 56, so that the weight 57 of the lever 55, aided by the spring 59, returns the control mechanism to normal initial position, with the stop roller 51 stopped against the stop-nosing 46, in which position the clutch mechanism of the drum 29 is released and the drum is stopped. Since, however, it is desirable to immediately operate the drum 37 to return the carriage and fork outward over the load, so the fork may descend, the operator when relaxing the rope or line 56, does so with a quick movement, so that the control lever 55 and bell-crank device will by its momentum cause the yieldable stop-roller 51 to ride over the stop-nosing 46, thus allowing the control lever and bell-crank device to make a complete swing to the right. Such operation causes the arm 44 of the bell-crank device to push onward the link bar 66, and to

consequently move outward the wedge-plate 61, with the result that the drum 37 is shifted to throw its clutch mechanism into operation, whereby rotative power is transmitted to the drum 37 through the gear 70 wheel 35, and thereupon the carriage returns along its track under the pull of the rope wound up on the drum 37. When the drum 37 is thus operating the main drum 29 is released so that the hay-fork hoist rope 75 attached thereto will unreel as the carriage returns to original position over the load and the hay-fork descends (this described operation of the hoist control mechanism is illustrated by the dotted representation of the same shown in Figure 3 and indicated by the reference character *y*).

From the above description the convenience and efficiency of the control mechanism will be readily understood by those skilled in the art to which this invention relates.

Referring now to Figures 8 and 9 of the drawings, I have illustrated therein a type of double drum hoisting machine, in which the separate fixed shaft 34 has been eliminated, and the auxiliary hoisting drum 37 is shown loosely mounted with its clutch mechanism upon the drive shaft 13, the latter having a larger gear wheel 80 fixed thereon, which meshes directly with the gear wheel 18 operating the main drum. The above described single lever control mechanism for the hoisting drums of this simplified arrangement of mechanism, is, in all substantial respects, constructed in the same manner and functions in the same manner as already above described, and as will be evidenced by the use of the same reference letters to identify the corresponding parts. There is one slight difference, however, to which attention may be called. This difference consists in mounting the thrust block 64 loosely upon the shaft 13, and providing the same with keeper lugs 81 which straddle the wedge-plate 61, whereby the thrust block 64 is held against rotation with the shaft 13. A collar 82 fixed by a set screw 83 may be arranged on the shaft 13 in back of the thrust block 64, whereby the latter may be set up or adjusted relative to the wedge-plate and the drum 37 actuated thereby.

Referring to Figures 10 and 11 of the drawings, I have illustrated therein another modified arrangement of the single lever control mechanism for selectively operating the hoist drums. In this modified arrangement, instead of mounting the yieldable stop means in connection with the bell-crank device and associated parts as above described, I eliminate said yieldable stop means from such connection, and provide in association with the wedge-plate 61 a yieldable stop means of somewhat similar character. In this modified form and location,

said yieldable stop means comprises a stop-nosing 84 which is suitably located on the upper edge of said wedge-plate 61. Mounted on the shaft 34 is a thrust-block 85 provided on its inner face with thrust lugs 86 against which the wedge-plate 61 bears. Connected with the upper side of said thrust-block 85, and so disposed as to overhang said wedge-plate 61 is a housing member 87. Said housing member 87 is provided at its lower or under side with a socket 88 in which is arranged a stop-roller 89. Extending upwardly through said housing member 87 above said socket 88 is a vertical bore 90 in which is arranged a compression spring 91, which thrusts downwardly upon said stop-roller 89 to yieldably engage the latter with the upper edge of said wedge-plate 61. The tension of the spring 91 is regulated by an adjusting screw 92 which is threaded into the bore 90 from the upper end of said housing member 87. When the parts of the single lever control mechanism are in normal initial or neutral position (as shown in Figure 10), the stop-nosing 84 is held stopped against the stop-roller 89. When operating the mechanism to throw in the clutch devices of the drum 37, the control lever 55 will be allowed to drop with a quick movement, so that wedge-plate 61 will be suddenly forced forward whereby its stop-nosing 84 will force upwardly the spring pressed stop-roller 89, thus allowing the wedge-plate 61 to move forward or outward, with the result that the drum 37 is shifted to throw its clutch mechanism into operation.

I am aware that some changes may be made in the mechanical design and in the arrangements and combinations of the several devices and parts of the novel hoisting mechanism above described, as well as in the details of the construction thereof, without departing from the scope of this invention as set forth in the foregoing specification, and as defined in the appended claims. Hence, I do not limit my invention to the exact arrangements and combinations of the devices and parts as described in said specification, nor do I limit myself to the exact details of the construction of said parts as illustrated in the accompanying drawings.

I claim:

1. In a power hoist, the combination with a plurality of drums, a shaft on which each drum rotates, a power transmission means, a clutch means intermediate each drum and said power transmission means, a single lever control mechanism fulcrumed on one of said drum supporting shafts for intermittently and alternately shifting said drums into clutched relation to said power transmission means, a housing member affixed to said single lever control mechanism adjacent

to its fulcrum, an upwardly yielding spring-pressed roller mounted in said housing member, a stationary stop-nosing engageable by said roller to determine the neutral drum releasing position of said control mechanism. 70

2. In a power hoist, a supporting frame, a plurality of drums a shaft mounted on said supporting frame for supporting each drum, a power transmission means, a clutch means intermediate each drum and said power transmission means, a single lever control mechanism comprising a bell-crank device having a fulcrum sleeve pivoted on the shaft of one of said drums, a single control lever affixed to one arm of said bell-crank device, said supporting frame having a stationary end thrust cam, said fulcrum sleeve having a rotatable end thrust cam to cooperate with said stationary end thrust cam, a stationary thrust block on the shaft of the other of said drums, a wedge-block slidable between said thrust block and the hub of said latter drum, a link-bar interconnecting said wedge-block with the other arm of said bell-crank device, and a yieldable detent means for determining the neutral drum releasing position of said single lever control mechanism. 85

3. In a power hoist, a supporting frame, a plurality of drums, a shaft mounted on said supporting frame for supporting each drum, a power transmission means, a clutch means intermediate each drum and said power transmission means, a bell-crank device having a fulcrum sleeve pivoted on the shaft of one of said drums, a single control lever affixed to one arm of said bell-crank device, said supporting frame having a stationary end thrust cam, said fulcrum sleeve having a rotatable end thrust cam to cooperate with said stationary end thrust cam, a stationary thrust block on the shaft of the other of said drums, a wedge-block slidable between said thrust block and the hub of said latter drum, a link-bar interconnecting said wedge-block with the other arm of said bell-crank device, a yieldable stop means carried by said bell-crank device, and a stationary stop-nosing connected with said supporting frame and engageable by said yieldable stop means to determine the neutral drum releasing position of said bell-crank device and associated parts. 105 110 115

4. In a power hoist, a supporting frame, a plurality of drums, a shaft mounted on said supporting frame for supporting each drum, a power transmission means, a clutch means intermediate each drum and said power transmission means, a bell-crank device having a fulcrum sleeve pivoted on the shaft of one of said drums, a single control lever affixed to one arm of said bell-crank device, said supporting frame having a stationary end thrust cam, said fulcrum sleeve having a rotatable end thrust cam to cooperate with said stationary end thrust cam, a 120 125 130

- stationary thrust block on the shaft of the other of said drums, a wedge-block slidable between said thrust block and the hub of said latter drum, a link-bar interconnecting 5 said wedge-block with the other arm of said bell-crank device, a housing member affixed to said bell-crank device above the fulcrum sleeve thereof, an upwardly yielding spring-pressed roller mounted in said housing member, a stationary stop-nosing connected with 10 said supporting frame and yieldably engageable by said roller to determine the neutral drum releasing position of said bell-crank device and associated parts.
- 15 5. In a power hoist, the combination with a plurality of drums of power transmission means, clutch means intermediate said drums and said transmission means, a single lever control mechanism for intermittently and 20 alternately shifting said drums into clutched relation to said power transmission means, a pull rope for controlling operative oscillation of said single lever control mechanism in one direction, a weight on said single 25 lever control mechanism for producing operative oscillation thereof in the opposite direction, and spring means for holding said single lever control mechanism in neutral position.
- 30 6. In a power hoist, the combination with a plurality of drums of power transmission means, clutch means intermediate said drums and said transmission means, a single lever control mechanism for intermittently and 35 alternately shifting said drums into clutched relation to said power transmission means, a pull rope for controlling operative oscillation of said single lever control mechanism in one direction, a weight on said single 40 lever control mechanism for producing operative oscillation thereof in the opposite direction, a yieldable stop means carried by said single lever control mechanism, and a stationary stop-nosing engageable by said 45 yieldable stop means to determine the neutral drum releasing position of said control mechanism.
- 50 7. In a power hoist, a supporting frame, a plurality of drums, shafts mounted on said supporting frame for respectively supporting each drum, a power transmission means, a clutch means intermediate each drum and said power transmission means, a bell-crank device having a fulcrum sleeve pivoted on 55 the shaft of one of said drums, a single control lever affixed to one arm of said bell-
- crank device to extend obliquely therefrom, said supporting frame having a stationary end thrust cam, said fulcrum sleeve having a rotatable end thrust cam to cooperate with 60 said stationary cam, a stationary thrust block on the shaft of the other of said drums, a wedge-block slidable between said thrust block and the hub of said latter drum, a link bar interconnecting said wedge-block with 65 the other arm of said bell-crank device, a pull rope for controlling operative oscillation of said control lever in one direction, a weight on said control lever to produce oscillation thereof in the opposite direction when 70 said pull rope is relaxed, and a yieldable detent means for determining the neutral drum releasing position of said control lever.
8. In a power hoist, a supporting frame, a plurality of drums, shafts mounted on said supporting frame for respectively supporting each drum, a power transmission means, a clutch means intermediate each drum and said power transmission means, a bell-crank device having a fulcrum sleeve pivoted on 75 the shaft of one of said drums, a single control lever affixed to one arm of said bell-crank device to extend obliquely therefrom, said supporting frame having a stationary end thrust cam, said fulcrum sleeve having a rotatable end thrust cam to cooperate with 80 said stationary cam, a stationary thrust block on the shaft of the other of said drums, a wedge-block slidable between said thrust block and the hub of said latter drum, a link bar interconnecting said wedge-block with 85 the other arm of said bell-crank device, a pull rope for controlling operative oscillation of said control lever in one direction, a weight on said control lever to produce oscillation thereof in the opposite direction when 90 said pull rope is relaxed, and a housing member affixed to said bell-crank device above the fulcrum sleeve thereof, an upwardly yielding spring-pressed roller mounted in said housing member, a stationary stop-nosing connected with said supporting frame and yieldably engageable by said 95 roller to support said weighted control lever so as to determine the neutral drum releasing position of said bell-crank device and associated parts.
- In testimony, that I claim the invention set forth above I have hereunto set my hand this 7th day of February, 1924.

JOHN FARRELL.
